(57) CLAIM

The ornamental design for a set of armchairs, as shown and described.

DESCRIPTION

FIG. 1 is a bottom view of a set of armchairs showing my new design;

FIG. 2 is a front view thereof;

FIG. 3 is a left side view thereof, the right side is a mirror image of the left side;

FIG. 4 is a rear view thereof; and,

FIG. 5 is a top view thereof.

The broken lines in the figures show portions of the set of armchairs which form no part of the claimed design.
